CONTROL MEANS FOR PORTABLE ELECTRIC TOOLS

Reynold Happe, Pittstown, N. J., assignor to The Singer Manufacturing Company, Elizabeth, N. J., a corporation of New Jersey

Application September 4, 1944, Serial No. 552,589

10 Claims. (Cl. 200—157)

1

This invention relates to portable electric tools and, more particularly, to the switch mechanism thereof. It has for its primary object a switch mechanism of simple and effective construction, automatic in operation in the sense of requiring no special manipulation by the operator to effect the opening and closing of the switch at times appropriate to the work in hand, and capable of organization as a convenient unit for ready installation in the handle of any particular tool.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings:

Fig. 1 is a broken-out sectional view illustrating the preferred form of switch mechanism installed in the handle of a portable electric tool.

Fig. 2 is a somewhat diagrammatic, sectional view, with parts broken out, to illustrate the functioning of the switch.

Fig. 3 is a section on the line 3—3 of Fig. 1.

Fig. 4 is a perspective view of the switch contacts and associated elements.

Fig. 5 is a perspective view of a switch actuating element and its supporting stud.

Referring to the drawings, the rear end 10 of the housing of a portable electric tool, such as a drill, is shown as terminating in a pistol grip handle 11 of generally hollow construction and partially open at the rear. The handle is closed at the bottom by a butt plate 12 on the inner face of which is anchored the current-supply cable 13. The current leads pass from this point to the switch unit and thence to the motor mounted in housing 10.

The rear bearing of the motor shaft is mounted in a support 14 carried by the frame of the motor and to which the handle is secured by screw 15. Depending from an insulating block 42, secured to the support 14, are two spring contacts 16 connected to the motor through leads 17 (only one of the contacts and one of the leads being shown). The switch unit, below described, is so organized that when inserted in the handle, appropriate contacts carried by the unit engage the fixed, spring contacts 16.

The switch unit comprises a housing generally designated 20, and manual actuating means generally designated 30; a portion of the unit being

2

bodily insertable into the handle 11 through the opening in the rear thereof. The switch unit is adapted to be secured to the handle by screws 18. Within the housing 20 is a snap-switch of any suitable construction. As illustrated, it comprises two sets of stationary, spring contacts 22 and 23 the adjacent, free ends of which are separated by a sliding contact member 25 consisting of a block of insulating material carrying the contact pieces 26. The contacts 22 are connected respectively to the leads 19 from cable 13, and the contacts 23 carry contact buttons 24 adapted to engage the spring contacts 16 when the unit is inserted into the handle, as above stated. The sliding movement of contact member 25 may be limited as by stops 46 (Fig. 2). In the upper position of the contact member 25 the circuit is broken. In the lower position of the contact member the circuit is closed by the contact pieces 26 respectively bridging pairs of contacts 22 and 23.

Movement of the sliding contact member 25 is effected by a snap-action spring 28 adapted to be thrown from the Fig. 2 (open-circuit) position, through dead-center, to a closed circuit position represented by the dash-and-dot line designated 40. As indicated, one end of the spring 28 engages a lug 27 projecting from sliding contact member 25, and the other end of the spring surrounds a pin 29 projecting from an actuator 31, the sliding movements of which effect the throwing of the snap-spring 28.

The upper end of actuator 31 is provided with bent up, spaced, wing portions 34. As shown in Figs. 1, 2 and 3, the actuator is mounted within a channel member 43 secured to the housing 20. Sliding movement of the actuator within the channel member is limited by suitable stops, as indicated at 33. These stops are provided by bosses on the member 43, which bosses are internally threaded to receive the screws 18. A track member 32 is secured to the back of the member 43 (Fig. 3) and receives rollers 38 to be referred to later. The actuator 31 is biased toward its Fig. 2 (open-circuit) position by a pair of springs 41 the lower ends of which are anchored on a cross-pin 44 extending through the side-walls of the channel member 43. The upper ends of springs 41 are anchored on a cross-pin 35 which extends through the actuator wings 34.

According to the present invention, the snap-switch is actuated by a member mounted for bodily, rectilinear movement relatively to the tool itself and so located as to be engaged by the hand of the operator, and moved to switch-clos-

ing position, without special attention by the operator, that is, as an incident of his normally grasping the handle of the tool and applying the tool to the work. Also, such member is so arranged as to constitute a part of the switch unit assembly.

For these purposes there is provided in this instance a grip-member 37 located along the rear of the pistol-grip handle 11 and suitably shaped to fit the contour of the body of the handle for convenient engagement by the palm of the hand of the operator when the tool is grasped. As indicated in Fig. 1, the grip-member 37 is located between channel walls 45 formed integral with the handle 11. Projecting from the inner face of grip member 37 is a block 47 which carries rollers 38 located within the track member 32. By reason of this construction the grip-member is movable longitudinally of, but is retained against outward removal from, the track member. Projecting from the block 47 is a stud 36 the outer end of which carries the cross-pin 35, thereby connecting the grip-member 37 to the wing portions 34 of the actuator 31. The actuator is thus positively operated by longitudinal movement of the grip-member relatively to and in the direction dictated by the track member.

In this preferred form of the invention the track member is set at what, for identification, will be referred to as an acute angle to the major longitudinal axis, i. e. the work-thrust axis, of the tool housing 10. More specifically, the track member may be said to be arranged substantially parallel to the axis of the handle of the tool, which axis, as usual, is set at an angle to that of the tool. As the result, when the operator grasps the tool and applies a normal work thrust to it in the direction indicated in Fig. 1, the grip-member slides or rides up the rear of the handle, in opposition to the springs 41, in the direction of motion indicated in Fig. 1 and thereby automatically throws the snap-switch to close the motor circuit. This condition continues, of course, just so long as the operator continues to apply work thrust to the tool. As soon as such thrust is relieved, springs 41 restore the grip-member 37 to its former position and coincidentally throw the snap-switch spring 28 to its circuit-opening position.

The described mechanism thus incorporates the combination of a snap-switch, having its own contact-actuating spring, and additional spring-controlled means for operating the snap-switch, the spring or springs of such additional means acting to bias the same in a direction to throw the snap-switch to its open-circuit position. As will be understood, the bias of such additional spring (in this instance the springs 41) is sufficient to overcome the resistance to switch-opening opposed by spring 28 when the latter is in its switch-closing position.

It will be noted also that there is nothing critical about the extent of movement required of the grip-member to close the switch, any movement sufficient to throw the snap-spring beyond its dead center position being sufficient. Nor is undue pressure required to maintain the switch closed. As soon as the snap-spring has passed its dead-center position, and unless the actuator is moved clear to the upper limit of its travel into engagement with upper stop 33 (which is quite unnecessary), the thrust of the snap-spring actually opposes the switch-opening tension of springs 41, with the result that the thrust necessary to maintain the switch closed

is represented simply by the necessary excess of the tension of springs 41 over the expansive force of spring 28.

Having thus set forth the nature of the invention what I claim herein is:

1. In a portable electric tool including a housing and a motor therein, a hollow handle attached to said motor housing, said handle being set at an acute angle to the work thrust axis of the tool, a motor switch located within the handle, a manually operable member for operating said switch, said member mounted for bodily sliding movement relatively to the handle, said movement being in a direction substantially parallel to the axis of said handle and therefore movable at an acute angle to the work thrust axis of the tool.
2. In a portable electric tool including a housing and a motor therein, a hollow handle attached to said motor housing, a motor switch within the handle, a bodily slideable hand-grip member for operating said switch, said member being located along the rear of the handle and shaped to the contour thereof, and track means for guiding said member to slide at an acute angle to the work-thrust axis of the tool.
3. In a portable electric tool including a housing and a motor therein, a hollow handle attached to said motor housing, said handle being set at an acute angle to the work thrust axis of the tool, a motor switch within the handle, a bodily slideable member for operating said switch, said member being located and arranged to form the rearwardly directed, thrust-receiving portion of the handle, and means for guiding said member for sliding movement at an acute angle to the direction of thrust applied thereto.
4. In a portable electric tool including a housing and a motor therein, and a hollow handle for manipulating the tool, a motor switch control unit bodily insertable into and removable from the handle and comprising a switch housing and switch, means for securing the switch housing, and thereby the unit, to the handle, track means supported on the switch housing and extending at an acute angle to the axis of the portable tool, and a manually-operable, switch controlling member mounted for bodily, sliding movement on said track means relatively to the unit and tool handle.
5. In a portable electric tool including a housing and a motor therein, and having a hollow handle, the combination therewith of a snap-switch for the motor mounted within the handle, said switch including a contact-actuating spring, track means within the handle set at an acute angle to the work-thrust axis of the tool, a hand-grip switch operating member mounted at the rear of the handle for bodily sliding movement relatively thereto upon said track means, and spring means biased to move said member from a closed-circuit position toward an open-circuit position in opposition to the thrust of the contact-actuating spring of the said snap-switch.
6. In a portable electric tool including a housing and a motor therein, and having a hollow handle, the combination therewith of a snap-switch for the motor mounted within the handle, said switch including a contact-actuating spring, a hand-grip member associated with the handle and slideable on the rear thereof and relatively thereto, switch-actuating means connected to the grip member, and a second spring acting to bias the switch-actuating means and grip member toward the open-circuit position of the snap-switch,

the bias of said second spring being sufficient to overcome the resistance to switch opening opposed by the contact-actuating spring.

7. In a portable electric tool including a housing and a motor therein, and having a hollow handle, the combination therewith of a snap-switch for the motor mounted within the handle, a hand-grip member mounted for sliding movement relatively to the handle at an acute angle to the work-thrust axis of the tool and located for engagement by the hand of the operator grasping the tool handle, and means responsive to such movement of the hand-grip member for actuating said switch.

8. In a portable electric tool including a housing and a motor therein; a hollow handle attached to said motor, said handle being set at an acute angle to the work-thrust axis of the tool; at least one stationary electric contact; at least one movable electric contact; spring means selectively movable either to a position for closing said contacts or to a position for opening said contacts; an actuator for said spring to move said spring from either of said positions to the other of said positions; a second spring for normally biasing said actuator to the position for moving said spring to the contact opening position; a grip member mounted to slide along said handle in a direction of motion that forms an acute angle to the normal thrust direction of said tool, said grip member being attached to said actuator, whereby, when said actuator is biased to the contact opening position, said grip member will be retracted into inactive position, and whereby when thrust is applied to said handle in a direction parallel to the normal thrust direction of said tool, said thrust will cause said grip member to slide along said handle against the bias of said second spring and thereby cause said actuator to move to the contact closing position.

9. In a portable electric tool including a housing and a motor therein; a hollow handle attached to said motor, said handle being set at an acute angle to the work-thrust axis of the tool; an electric switch mounted in said handle; an actuator for opening and closing said switch; a channel member supported in said handle and in which said actuator is mounted; a spring for normally biasing said actuator to open said switch; channel walls formed integral with said han-

dle; a grip member mounted to slide along said handle within said channel walls in a direction of motion that forms an acute angle to the normal thrust direction of said tool; said grip member being attached to said actuator, whereby, when said actuator is biased to the position for opening said switch, said grip member will be retracted into inactive position, and whereby when thrust is applied to said handle in a direction parallel to the normal thrust direction of said tool, a component of said thrust will cause said grip member to slide along said handle against the bias of said spring and thereby cause said actuator to move to the position for closing said switch.

10. In a portable electric tool including a housing and a motor housed therein; a hollow handle attached to said motor housing and set at an acute angle to the work thrust axis of the tool; an electric snap switch housed in said handle and normally biased to an inactive position; an actuator formed as a part of said switch; a pair of apertured wing portions formed integral with said actuator; a cross pin passing through the said apertured wing portions; a threaded stud pivoted on said pin between said wing portions; a pair of track members supported in said handle and set at an acute angle to the work thrust axis of the tool; a plurality of rollers received in said track members; a grip member movably supported by said rollers and arranged to move in a direction parallel to the handle; and a means for securing said grip member to said threaded stud, whereby when said grip member is moved said switch is operated.
